UNITED STATES PATENT OFFICE.

HENRY CLAY, OF FERNWOOD, PENNSYLVANIA, ASSIGNOR TO JOHN SLINGLUFF, OF NORRISTOWN, PENNSYLVANIA.

PNEUMATIC-DESPATCH TUBE.

SPECIFICATION forming part of Letters Patent No. 603,174, dated April 26, 1898.

Application filed November 17, 1897. Serial No. 658,810. (No model.)

To all whom it may concern:

Be it known that I, HENRY CLAY, a citizen of the United States, residing at Fernwood, in the county of Delaware, State of Pennsylvania, have invented a new and useful Improvement in Pneumatic-Despatch Tubes, which improvement is fully set forth in the following specification and accompanying drawings.

10 My invention relates to an improvement in a pneumatic-despatch tube whose gate is adapted to be automatically opened by the pressure of air created by the advancing traveler, head, or carrier in said tube and then to 15 be automatically closed after the carrier has passed said gate.

The invention consists of novel means for directly effecting said opening and closing actions of the gate, and other features are 20 presented, as will be hereinafter set forth, and pointed out in the claims.

Figure 1 represents a longitudinal section of a pneumatic tube embodying my invention. Fig. 2 represents a partial top or plan view 25 and partial horizontal section on line xx , Fig. 1, on a reduced scale.

Similar letters of reference indicate corresponding parts in the figures.

Referring to the drawings, A designates a 30 pneumatic tube, and B designates one of the gates therein, said gate having its upper portion fitted in the guide C in the chamber or casing D above said tube.

Pivoted to the side of the gate is a link E, 35 to the upper end of which is freely connected one limb of an elbow-lever F, which is mounted on an ear F' in the chamber D. Supported within said chamber D is a standard G, containing an air-passage H, with which communicates one end of a pipe J, whose other end 40 communicates with the tube A.

Within the chamber D is an air-chamber K, which is supported in the present case on the standard G and communicates with the 45 passage or conduit H.

Telescopically fitted to the chamber K is the movable member L, with which is connected the bar or rod M, which is freely attached to the adjacent limb of the lever F, it 50 being noticed that in the present case said

member is hollow and located on said chamber K and has its outer end closed.

Aside of the chamber D is a chamber N, which is separated from said chamber D by the partition P, which in the present case 55 constitutes a portion of the guide C for the gate B. Within said chamber N is a bent lever Q, one limb Q' of which is pivoted to a link R, the latter being pivotally connected with the gate B on the side opposite to the 60 arms E. The other limb Q'' of said lever Q occupies a position adjacent to a slot S in the wall of the tube A, below the chamber N, in line with said slot, so as to enter the same, as will be hereinafter more fully explained. 65

As the carrier that travels in the tube A approaches the gate B the air in advance of the same is forced into the pipe J, passage H, and chamber K, and thus exerts its pressure on the member L and moves the same, whereby the lever F and arm E are operated to raise and open the gate B, the latter entering the chamber D, thus permitting the carrier to pass the same. As the gate rises or moves it operates the lever Q, whereby the limb Q'' 70 thereof passes through the slot S and enters the tube A in the path of the advancing carrier, as shown by the dotted lines in Fig. 1. When said carrier reaches said limb it engages therewith and raises it, thus closing 75 the gate, it being noticed that the operation of opening and closing the gate is automatically effected in either case. As the gate closes it operates the piston and connected parts, causing the seating of the gate in its 80 original position.

As some of the air that follows the carriers may pass through the slot S into the adjacent chamber N, it is prevented from escaping backward owing to the partition P, which 90 closes the rear end of said chamber.

In the chamber K, near the rear end thereof, is a port a, and in the side wall of the member or element L, near the front end thereof, is a port b, whereby when said member has advanced or moved to the required extent said ports are placed in communication, and thus the air in said chamber may escape to prevent further movement of said member and relieve the same of a cushion 95 100

that would otherwise interfere with the return motion of said member.

- The tube A is provided with branches, as shown in Fig. 2, one of which leads from said tube to an intermediate station and the other branch leads from the latter back to said tube. In such cases the tube is provided with a switch (not shown) at the intersection of the tube and the first-named branch. It will be understood that a gate is employed in the main tube A beyond the place of intersection of the branch of an intermediate section, so as to direct the fluid or air into said branch. Again in some cases a new source of supply of fluid or air may be required to be admitted into the main tube beyond said gate, so that the latter as closed will prevent such fluid or air from flowing into the tube in the opposite direction to that shown by the arrows, Fig. 1. These provisions admit of the construction of the tube of a pneumatic-despatch system of an indefinite length having a new supply of fluid or air at intervals, as may be required, the continuity of the main tube, however, being preserved and the same set of carriers serving from end to end of the system, entering the sections consecutively.

Having thus described my invention, what I claim as new, and desire to secure by Letters Patent, is—

1. A pneumatic-despatch tube having a gate, an air-chamber in direct and unobstructed communication with said tube in advance of said gate, a movable member fitted to said chamber and a connection common to said member and gate whereby the latter may be directly opened by the pressure of the air or fluid intermediate of said gate and the advancing carrier.
2. The combination of a pneumatic-despatch tube, a gate located therein, an air-chamber in communication with said tube, a movable element operated by air-pressure and supported by said chamber, a connection common to said gate and element, means connected with said gate for closing the same, one end of said means being adapted to enter said tube beyond said gate, a chamber located adjacent to the latter and inclosing said air-chamber and gate-closing means, and a partition intermediate of the latter and said gate.
3. The combination of a pneumatic-despatch tube, a gate located therein, an element operated by fluid-pressure, means for conducting said pressure directly to said element from a point in front of said gate, a connection common to said element and gate whereby the two latter operate in unison and mechanism connected with said gate for closing the same, said mechanism being positively operated by the progression of the carrier beyond said gate.
4. In a pneumatic-despatch tube, a gate and means for automatically opening the same by the air-pressure created by an advancing carrier, the conduit for said air having a direct and unobstructed communication with

said tube in combination with mechanism connected to said gate for closing the latter and means for enabling said mechanism to be positively operated by the progression of said carrier beyond said gate.

5. A pneumatic tube having a sliding gate therein, a chamber above said tube, a standard with an air-passage therein, a pipe leading from said tube to said air-passage, an air-chamber supported on said standard and in communication with said air-passage, a member movable on said air-chamber, and adapted to close one end thereof, and a lever and link connecting said gate and member.

6. A pneumatic-despatch tube having a gate, an air-chamber communicating with said tube, a member movable on said chamber, means connecting the movable member on said chamber and the gate on one side of the latter, means connected with the other side of the gate for closing the same and having one end adapted to enter a slot in said tube in position to be struck by a carrier and a partitioned casing beside said pneumatic tube and in which the operating mechanisms are located.

7. A pneumatic tube having a gate with levers connected therewith on opposite sides, for opening and closing the same, an air-actuated member which is connected with the opening-lever, and an air-chamber and a pipe in communication with said member and tube, the closing-lever being adapted to enter a slot in said tube, so as to be in the path of the advancing carrier in the tube.

8. In a pneumatic-despatch tube system, a gate in the tube thereof, an air-chamber in communication with said tube, a movable member fitted to said chamber and a connection common to said member and gate, said chamber and member being respectively provided with ports which are adapted to be placed in communication when said member has been sufficiently operated.

9. In a pneumatic-despatch tube system, a main tube having a gate within the same, an air-chamber in direct and unobstructed communication with said tube in advance of said gate, a movable member fitted to said chamber, a connection common to said member and gate, whereby the latter may be directly opened by the pressure of the fluid intermediate of said gate and an advancing carrier, branches connected with said tube on opposite sides of said gate, one of said branches leading to an intermediate station at the end of a section, and the other branch being adapted to be connected with a new source of fluid or air supplying a new section at the beginning thereof, the continuity of said main tube being preserved.

HENRY CLAY.
